UNITED STATES PATENT OFFICE.

GEORGE THOMSON SANDERSON AND THOMAS BOLAND, OF GALASHIELS, SCOTLAND.

DRIVING APPARATUS FOR SPINNING, DOUBLING, AND TWISTING MACHINERY.

Application filed June 17, 1924. Serial No. 720,617.

To all whom it may concern:

Be it known that we, GEORGE THOMSON SANDERSON and THOMAS BOLAND, respectively residing at Old Gala House, Galashiels, 5 in the county of Selkirk, Scotland, and 45 Woodside Place, Galashiels, aforesaid, have invented certain new and useful Improvements Relating to Driving Apparatus for Spinning, Doubling, and Twisting Machinery, of which the following is a specification.

This invention relates to improvements in the method of and means employed for reversing the direction of rotation of the 15 band cylinders on spinning mules and all other spinning and twisting machinery, and also in the case of mules for controlling the speed of winding. The mule in its present state of construction is fitted with two 20 cylinders, one at each side of the headstock and reaching to each end of the carriage. These cylinders are driven by a band from the rim pulley to a grooved pulley in the carriage. This grooved pulley 25 is fixed on a shaft on which is also fixed the winding motion, and the backing off motion. For reversing the direction of rotation of the band cylinders of spinning mules and other spinning and twisting machinery, it has been proposed to interpose 30 gearing between a driving shaft and the band cylinder or cylinders so that while the driving shaft revolves continually in one direction, the cylinder or cylinders may 35 be revolved in either direction as desired by the manipulation of the intermediate gearing.

According to this invention instead of the drive being transmitted directly to the 40 band cylinder it is transmitted to a countershaft which extends wholly or mainly throughout the length of the machine and drives the cylinder or cylinders at the end or ends that are remote from the headstock or driving end of the machine through 45 the intervention of gearing which is so constructed and arranged that the cylinder or cylinders can be driven in either direction at will and also at a speed which can be 50 regulated to suit any particular class of yarn.

In applying the invention to a spinning mule the band drive is transmitted from the rim pulley to a countershaft which extends wholly or mainly throughout the length of the carriage and drives the cylinder or cyl-

inders at the end or ends which are remote from the headstock through the intervention of gearing which will enable the cylinder or cylinders to be driven in either direction at will and at any predetermined speed.

The countershaft is introduced in the mule carriage in the place where the cylinder is ordinarily mounted and the latter is brought forward, or nearer to the centre of the carriage. The band drive from the rim pulley to the grooved pulley is then transmitted to the countershaft instead of to the cylinder and the drive is transmitted from the countershaft to the cylinder by gearing which is mounted at the end or ends of the carriage as aforesaid and as the countershaft is also driven by the winding motion the winding speed can be controlled by altering the gearing between the cylinder or cylinders and the countershaft.

In applying the invention to a ring spinning, or other like frame, the band cylinder or cylinders may be raised and the countershaft placed underneath them. In this case the drive would be transmitted to the countershaft at the headstock or driving end of the machine and from the countershaft to the band cylinder or cylinders through the intervention of gearing as aforesaid at the end of the machine that is remote from the headstock or driving end.

In order that the said invention may be clearly understood and readily carried into effect, the same is described more fully with reference to the accompanying drawings which show the invention applied to a spinning mule.

Figure 1 is a plan view of a mule carriage provided with driving mechanism according to this invention. Figs. 2 and 3 are left and right hand views of the carriage, and are drawn to a larger scale. Fig. 4 is an end view, and Fig. 5 is a plan view, showing the driving mechanism arranged for ordinary direction of driving.

The band cylinders D are placed nearer the center of the carriage B than they are ordinarily placed, and a countershaft E is journaled in the carriage parallel to them. A pulley d is secured on the countershaft, and is driven by a band c from a driving pulley C, and when winding it is driven by the winding motion. Toothed wheels e are secured on one or both ends of the shaft E and gear into toothed wheels d² on the shaft of the

band cylinder as shown in Figs. 2 and 3, when it is required to drive the cylinder in the reverse direction. To drive the cylinder in the ordinary direction the wheels e and d^2 are replaced by smaller wheels e^1 and d^3 , as shown in Figs. 4 and 5, and these small wheels are connected by an idle toothed wheel G mounted on a pin g .

Any change can be made in the size of the wheels on the cylinder shaft and countershaft for controlling the speed of winding. If two 40 toothed wheels are necessary for imparting a minimum tension to the yarn when winding, then a 45 and a 35 toothed wheel or a 43 and 37 toothed wheel or any other change can be made to suit the count or quality of the yarn and any speed at which the cylinder is rotated can be raised or lowered to increase or diminish production.

The details of construction can be variously modified without departing from the nature of the invention, for example any form of change speed gear and reversing gear between the countershaft and the cylinder can be substituted for the one described.

By the invention described it is possible, in certain classes of yarn, to considerably increase the speed of the cylinder or cylinders, and in this way there would be an increase in the amount of yarn which could be wound on to each pim. The spinner can if he so desires use the winding motion without the reverse motion and thus get ordinary twist. For this purpose he could if he so desired, cross his driving bands and drive the band cylinder by two geared wheels, one on the countershaft and the other on the band cylinder shaft. Uneven yarn produced when the rim pulley is not the exact size required can be eliminated by varying the gearing at the end of the countershaft and cylinder,

and without having to change the rim band pulley. The countershaft acts as a support or stay for the mule carriage and increases its rigidity. The apparatus is extremely simple and it can be applied to any spinning mule, doubling or twisting machinery for spinning, or twisting wool, worsted, linen, jute, silk and other fibres, with very little trouble and at a very small cost.

What we claim as our invention and desire to secure by Letters Patent in the United States is:—

1. In cylinder driving apparatus for spinning and twisting machinery, the combination of a countershaft, a band cylinder arranged parallel with the countershaft, means for transmitting motion to the countershaft, and gearing connecting the countershaft and band cylinder at the end that is remote from the driving end of the machine.

2. In cylinder driving apparatus for spinning mules, the combination with the headstock and carriage, of a countershaft extending along the carriage, a band cylinder arranged parallel with the countershaft, means for transmitting motion to the countershaft, and gearing connecting the countershaft and band cylinder at the ends that are remote from the headstock.

3. In cylinder driving apparatus for spinning mules, the combination with the headstock and carriage, of a countershaft extending along the carriage, a band cylinder arranged parallel with the countershaft at opposite sides of the headstock, means for transmitting motion to the countershaft, and gearing connecting the countershaft and band cylinders at the ends that are remote from the headstock.

In testimony whereof we affix our signatures.

GEORGE THOMSON SANDERSON.
THOMAS BOLAND.
